UNITED STATES PATENT OFFICE.

RICHARD H. TRESTED, OF GREENVILLE, NEW JERSEY.

HEAD-COVERING.

SPECIFICATION forming part of Letters Patent No. 257,787, dated May 9, 1882.

Application filed March 9, 1882. (Model.)

To all whom it may concern:

Be it known that I, RICHARD H. TRESTED, a citizen of the United States, residing at Greenville, in the county of Hudson and State 5 of New Jersey, have invented new and useful Improvements in Head-Coverings, of which the following is a specification.

My invention has reference to an improved hat for ladies' and children's use, which is made 10 from strips of fabric with nap on one or both sides, napped in imitation of plush, fur, sealskin, or beaver, and sewed together, either with or without straw or other braid.

In carrying out my invention I take a piece 15 of fabric, made from cotton or other similar substance, having a nap on one or both sides, cut the same into strips of any desired width, then sew them into the form of a hat. The strips can be one of fabric and one of straw or 20 other braid, or the strips cut from fabric can be of different colors, thus making a hat of a variety of shades, or the straw braid can be one color and the fabric another, thus producing a very desirable hat at a very low cost, 25 as a hat made from straw and fabric strips can be produced for about half the cost of a full straw-braid hat. After the strips are sewed into the shape of hat desired it can be sized and blocked in the same manner as 30 is usually practiced in the manufacture of hats or bonnets.

In the accompanying drawings, Figure 1 represents a sectional side view of a head-covering made according to my invention. Fig. 2 35 is a section of two braids, as sewed together.

Similar letters indicate corresponding parts.

In the drawings, the letter *a* designates a strip of napped fabric, and the letter *b* a straw braid or a strip of any other material.

40 I am aware of hats having been made from napped fabric, made from one or more thicknesses from one continuous piece or pieces of fabric. By this method only one color can be produced for the top and inside of the hat.

45 By this method there is also a great waste of fabric in pulling over the dies to form the hat,

as all the trimmings, after the hat is produced, are useless, only for waste rags. By my method of cutting into strips and sewing all the fabric is used; also, the hat can be made 50 into desirable colors by sewing each strip a different color, or I can sew up one strip of fabric and one of straw or other braid, thus producing a novelty obtained by no other process.

55 I am aware that head-coverings have been composed of annular connected bands of contrasting colors, said bands being made of felt or other unnaped fabric and straw alternately arranged, or all of said bands of one 60 and the same material. Such, however, is not broadly claimed by me, and does not constitute my invention, as I construct a hat of connected strips of fabric and straw, the former napped on one or both sides in imitation of 65 plush, fur, sealskin, or beaver, and to this my claims are restricted.

What I claim as new, and desire to secure by Letters Patent, is—

1. As a new article of manufacture, a hat 70 made of strips of napped fabric, napped either on one or on both sides, sewed or pasted together.

2. A lady's or child's hat of strips of cotton, silk, or woolen napped fabric, napped either 75 on one or both sides, and sewed into a hat alternating with strips of straw or other braid, sized and blocked into shape, substantially as specified.

3. The method herein described of making 80 ladies' and children's hats from strips of fabric napped on one or both sides, or napped fabric and straw or other braid sewed or stuck together, sizing and blocking the same into shape, substantially as set forth.

85 In testimony whereof I have hereunto set my hand and seal in the presence of two subscribing witnesses.

R. H. TRESTED. [L. S.]
